UNITED STATES PATENT OFFICE.

WILLIAM F. SCHANZLIN, OF LIMA, OHIO.

HIGH-PRESSURE STILL.

Application filed April 7, 1921. Serial No. 459,258.

To all whom it may concern:

Be it known that I, WILLIAM F. SCHANZLIN, a citizen of the United States, and a resident of Lima, in the county of Allen and State of Ohio, have invented a new and Improved High-Pressure Still, of which the following is a full, clear, and exact description.

My invention relates to high pressure stills of the type used in refining naphtha, gasoline and various other petroleum products.

More particularly stated, my invention relates to the manner of applying heat to the still and of causing circulation to take place in consequence of the heat.

I seek to provide means not merely for heating the liquid to be distilled but, in addition, for causing the liquid when thus heated to circulate vertically, so as to thoroughly distribute the heat throughout the entire mass of the liquid.

I employ as a still, a hollow member disposed horizontally, and in connection with this hollow member I use a number of drums connected together by tubes extending vertically, two of the drums being connected together by a throat in order to facilitate circulation.

By my invention, I seek to discard the necessity for tube plugs made of Monel metal, brass, lead or the like and to simplify the connection of the various parts, at the same time doing away with the necessity for excessive labor and cost in the matter of upkeep.

I further seek to prevent the deposit of carbon within the still and especially within the upper portions thereof.

Reference is made to the accompanying drawing forming a part of this specification, and in which like reference characters indicate like parts throughout the several figures.

Figure 1 is a vertical section through my improved apparatus.

Figure 2 is a fragmentary section showing my device as used in a manner somewhat different from that appearing in Figure 1.

A furnace 4 is provided with a firebox 5, and located at the base of the furnace is a drum 6. Connected with this drum is a pipe 7, serving as a tar line. Two other drums 8, 9 are mounted upon the furnace at a little distance over the drum 6. A

number of tubes 10, 11 are connected with the drum 6 and extend upwardly therefrom in two groups as shown, the upper ends of these tubes being connected with the drums 8, 9. A partition 12, made of fire clay tile boards dovetailed to fit each other is disposed between the tubes 10 and the tubes 11. The partition 12 is thus built up of units so that its height can be practically controlled at will—that is, by removing some of the tile boards or adding others. The flames and hot gases from the firebox heat all of the drums and circulate around and between the tubes 10 and 11, especially at the top portions thereof. The top of the furnace is bricked over at 13.

The drum 9 is provided with a head 14 extending upwardly from it as indicated in Figures 1 and 2. Where my invention is used as indicated in Figure 1, the head 14 is closed by a cap 15, held thereupon by bolts 16.

The body of the still appears at 17 and is in communication with the drum 8 by means of a trunk 18. The drum 9 is provided with a head 19 and detachably connected with the latter is a trunk 20. The still body 17 is provided with a vapor outlet 21 and also with manholes 22, 23, these three parts being of the usual or any desired construction. The still body 17 is further provided with a head 24 which is detachably connected with the trunk 20, when my device is to be used as indicated in Figure 1.

The still body 17 is further provided with a head 26. A trunk 27 is provided for the purpose of facilitating the connection with the head 14, as indicated more particularly in Figure 2. An auxiliary trunk 28, shown in Figure 2, is provided for use in connection with the still body 17. When this pipe is employed, it is located within the still body, and connected with the head 26 as indicated in Figure 2. A cap 25 is used for the purpose of closing the head 26 or the head 24, as the case may be—that is to say, where my invention is used as indicated in Figure 1, the cap 25 is detachably mounted upon the head 26 so as to close the same. When, however, my device is employed as indicated in Figure 2, the cap 25 is detachably mounted upon the head 24 so as to close the latter.

Somewhat similarly, the cap 15 is used to close either the head 14 or the head 19 carried by the trunk 9, according to

whether my device is used in the manner indicated in Figure 1 or that indicated in Figure 2.

Thus, it may be readily seen how my device may be employed in two different ways. When it is to be used as indicated in Figure 2, the trunk 27 is placed in between the heads 14 and 26, and detachably connected therewith, as shown at the left of Figure 2. In this event, the cap 25 is secured upon the head 24, and, of course, nothing else is connected with the head 24 for the time being. The trunk 28 is also placed in position and the cap 15 is placed upon the trunk 19 so as to close the same.

When, however, my device is used as indicated in Figure 1, the pipe 28 and trunk 27 are removed; the cap 25 is placed upon the head 26, and the cap 15 similarly placed upon the head 14, so as to close the same. This done, the trunk 20 is connected with the head 19 of the drum 9 and with the head 24 of the still body 17.

The operation of distillation as performed with either one of the two forms of my invention may be readily understood from the foregoing description. The petroleum or petroleum product to be distilled is placed within the still body 17, so as to fill up all of the drums and such trunks as are for the time being used for connecting the still body with the drums. Heat being applied by means of a fire in the firebox 5, the flames and hot gases raise the temperature of the tubes 10, 11 and heat the contents thereof. As the heated liquid tends to rise, a circulation is established, so that while the still is in action the liquid is flowing continuously through the tubes 10 and 11. More heat being applied to the liquid through the tubes 10 than through the tubes 11, owing to the closer proximity of the tubes 10 to the fire, the liquid within the tubes 10 is constantly rising, whereas the liquid within the tubes 11 is constantly falling. Thus, the circulation is maintained at a rate which is comparatively uniform and this means, of course, a flow of the liquid from left to right through the still body; hence, no particular part of the liquid remains for any great length of time in any fixed location. Because of the circulation just mentioned, the liquid operated upon is not violently broken up by excessive heat. What occurs is that the more volatile components of the liquid are continuously carried off as vapor. By the arrangement above described, undue carbonization is prevented from taking place.

The manner in which, during distillation, the different component liquids are separated by being formed into vapor, carried off and condensed by cooling is too well known to need any description.

Of course, in using any apparatus of this

general type upon petroleum or its products, more or less carbon is formed, and as a result there is a tendency for tar to accumulate and to become heavy. In my apparatus, the carbon and the tar drift downwardly into the drum 6 and are from time to time tapped off through the tar line 7. For this purpose, the drum 6 is made of rather large diameter.

It will be understood that at the same plant my invention can be used at one time in the manner contemplated by Figure 1 and at a different time in the manner indicated in Figure 2. It has been found in distilling some oils that due to the inequality in the expansion and contraction of the pipe 20 and a still body 17, leakage is liable to occur at the points of connection between the pipe 20 and the still body and the drum 9, and to obviate this difficulty the arrangement shown in Fig. 2 may be employed. In general it might be said that the above objection to the form of the apparatus shown in Fig. 1 prevails only when distilling lighter oils which lose their heat quickly by rapid radiation during their passage through the pipe 20 from the still 17 to the drum 9.

With the apparatus above described, the products derived from the process are of comparatively uniform grade, and relatively free from impurities.

I do not limit myself to the precise mechanism shown, as variations may be made therefrom, without departing from the spirit of my invention.

Having thus described my invention, what I claim as new and desire to secure by Letters Patent is as follows:

1. A high pressure still, comprising a furnace, a horizontally arranged drum in the lower part of the furnace, and having a pipe leading from the bottom thereof, a pair of horizontally arranged drums above the first drum, and disconnected from each other, a series of vertical tubes connecting the lower drum with each of the upper drums, a partition between the series of tubes, a horizontal elongated still body arranged outside of the furnace walls a short distance above and at right angles to the said drums, and pipes connecting the still body with the upper drums, the pipes being comparatively large and communicating with the said drums through correspondingly large openings.

2. A high pressure still, comprising a furnace, heating drums in the furnace at the top thereof and in proximity to each other, an elongated and horizontally disposed still body having one end arranged directly above and in spaced relation to the heating drums and outside of said furnace, the remaining portion of the still body extending beyond the said heating drums, a pipe con-

necting one of the heating drums with the end of the still body above said drum, and a pipe connecting the other heating drum with the still body, said last named pipe effecting communication between the said other drum and the other end of the still body, and which is remote from the heating drums.

3. In a high pressure still, comprising a still body, a furnace, heating drums disposed therein in proximity to one another, said still body lying above and transversely of the drums, one end of said still body extending laterally a substantial distance beyond the drums, the other end being adjacent to the heating drums, a conduit between one drum and the adjacent end of the still body, and a second conduit between the other drum and the still body and communicating with that portion of the still remote from

said drum, said conduit being disposed within the still body adjacent the bottom thereof and extending therefrom at a point adjacent to said other drum.

4. In a high pressure still apparatus, a still body, a thermal circulating system comprising a furnace, a sediment drum therein, a plurality of independent heating drums positioned above said sediment drum, a plurality of series of heating tubes connecting the sediment drum with the heating drums, insulating baffles between said series of tubes and between the heating drums and the still body, and conduits connecting the heating drums with the still body whereby a fluid circulating within the still may be heated on its passage to the still body and again on its passage therefrom.

WILLIAM F. SCHANZLIN.
